UNITED STATES PATENT OFFICE.

OLIVER W. CURTIS, OF WATERTOWN, NEW YORK.

STRIP-MARKER.

1,169,130.

Specification of Letters Patent.

Patented Jan. 25, 1916.

Application filed May 16, 1914. Serial No. 838,974.

To all whom it may concern:

Be it known that I, OLIVER W. CURTIS, a citizen of the United States, residing at Watertown, county of Jefferson, and State 5 of New York, have invented certain new and useful Improvements in Strip-Markers, of which the following is a specification.

The invention relates to such improvements and consists in the novel construction 10 and combination of parts hereinafter described and subsequently claimed.

Reference may be had to the accompanying drawings, and the reference characters marked thereon, which form a part of this 15 specification. Similar characters refer to similar parts in the several figures therein.

Figure 1 of the drawings is a view in side elevation of my improved strip-marker. Fig. 2 is a top plan view of the same, partly 20 broken away and partly shown in section. Fig. 3 is a front elevation of the same, partly broken away and partly shown in section. Fig. 4 is a vertical cross-section taken on the broken line 4—4 in Fig. 2. Fig. 25 5 is a view in front elevation, partly broken away and partly in vertical cross-section, taken on the broken line 5—5 in Fig. 2. Fig. 6 is a vertical cross-section taken on the broken line 6—6 in Fig. 2. Fig. 7 is a 30 cross-section taken through the axis of the gang of gears and the sleeve upon which they are mounted. Fig. 8 is a vertical cross-section taken on the broken line 8—8 in Fig. 7.

The principal object of the invention is to 35 automatically apply to a strip of flexible material, as the same is fed over a drum of constant diameter, marks at regular intervals of variable length at the will of the operator, which marks indicate points at which the strip can be severed to form sections of equal length adapted for various uses.

The apparatus shown in the drawings is 40 particularly adapted for thus marking a strip, sections of which are to be severed or stitched upon underdrawers to form waistbands therefor.

In carrying out my invention I employ 45 an ordinary crayon or lead-pencil in combination with a drum of constant diameter over which the strip is fed, with means for supporting the pencil and causing it to engage the strip at regular intervals in ac-

cordance with the angular movement of the 55 drum, provision being made for thus automatically actuating the pencil at the will of the operator at longer or shorter intervals, corresponding with greater or less angular movements of the drum. 60

Referring to the drawings wherein the invention is shown in preferred form, 1 is a standard having an upwardly extending bracket, 2, upon which is rotatively mounted the tape-supporting drum, 3. 65

Upon the body of the standard is rotatively mounted a reel, 4, which carries a supply of tape or binding-strip, 5, which strip passes from the reel over the drum, and thence to a guide, 6, from which it may 70 be passed directly to a sewing-machine, or to the operator, or elsewhere as may be desired.

The drum is of constant diameter, and has on its periphery a series of spurs, 7, which 75 engage the strip and cause the strip to positively rotate the drum as the strip is fed thereover. The drum, 3, is fixed upon a sleeve, 8, by means of an internal diaphragm, 9, within the drum, said sleeve, 8, 80 being mounted to rotate freely upon a horizontal shaft 10, which is fixedly mounted upon the bracket, 2.

A tapered gang of gear-wheels, 11, is feathered upon the sleeve, 8, to move longitudinally thereof as a unit, while rotating in connection with said sleeve and the drum, 3. 85

Sliding movement of the gang of gear-wheels, 11, longitudinally of the sleeve, 8, is induced by means of a yoke, 12, which 90 engages a groove, 13, in the hub, 14, of a sleeve, 15, upon which sleeve the gears, 11, are fixedly mounted, said sleeve being formed with an internal groove to receive the feather, 16, on the sleeve, 8. 95

The yoke, 12, is fixed upon the inner end of a gear-rack, 17, reciprocatory in a slide-way, 18, on the bracket, 2, in a vertical plane passing through the axis of the drum. The teeth on the rack, 17, are engaged by 100 a pinion, 19, fixed upon a shaft, 20, which extends perpendicularly to the rack, 17, and is rotatively mounted in a vertically-swinging-frame, 21, pivoted at 22, upon the bracket, 2. The outer end of the shaft, 20, 105 has fixed thereon a spiral cam, 23, the periphery of which is provided with a series of notches, 24, adapted to severally receive

a knife-edge, 25, which is fixedly mounted on an arm, 26, projecting from the bracket, 2.

The vertically-swinging frame, 21, has rotatively mounted therein a shaft, 27, parallel with the rack, 17, upon the inner end of which shaft is fixed a gear-wheel, 28, which is adapted to mesh with the several gears, 11, in various positions assumed by the vertically-swinging frame, 21. Upon the outer end of the shaft, 27, is fixed a gear-wheel, 29, which meshes with a gear-wheel, 30, fixed upon a shaft, 22, which forms the pivot for the vertically swinging-frame, 21.

15 The crayon or pencil, 31, is clamped upon the end of an arm, 32, projecting from a slide, 33, which slide is adapted to reciprocate vertically in a slideway, 34, on an upward extension of the bracket, 2.

20 The slide, 33, has near its lower end an offset 35; and a coil-spring, 36, is yieldingly confined between said offset, 35, and the top-wall of a recess in the slideway, 34, tending to yieldingly hold the slide, 33, depressed. The slide, 33, also has upon its lower end a follower-roller, 37, adapted to engage a cam, 38, fixed upon the shaft, 27, which cam is formed with a notch, 39, adapted to permit the follower, 37, and slide, 33, to drop sufficiently to permit the pencil to engage and make a mark upon the strip on the drum.

25 The notches, 24, in the periphery of the spiral cam, 23, are spaced apart to correspond with different lengths of strip to be indicated by marks of the pencil, 31; and the spiral form of said cam is such that as the cam is rotated to bring its portions of larger diameter opposite the knife-edge, 25, it will through the shaft, 20, pinion, 19, rack, 17, and yoke, 12, slide the gang of gears along the sleeve, 8, to bring one of the larger gears, 11, opposite the gear-wheel, 28, while at the same time the swinging-frame, 21, will, by engagement of the surface of the cam, 23, with the knife-edge, 25, be supported in a sufficiently higher position to permit the gear, 28, to properly engage and mesh with the proper gear, 11. It will thus be seen that by properly proportioning the various gears, 11, with relation to the diameter of the drum, 3, and the positions of the notches, 24, a greater or less angular movement of the drum, 3, can be caused to produce a uniform angular movement of the shaft, 22, and the pencil-actuating cam, 38. For example, when sections of considerable length are to be marked on the strip, one of the smaller gears, 11, is caused to mesh with the gear, 28, said gears being in such ratio to each other that when the drum has traveled a distance, measured circumferentially, equal to the length of the strip-section to be marked, one complete rotation will be imparted to the shaft, 22, and cam, 38; and for

successively shorter lengths of strips to be marked, successively larger gears, 11, will be caused to mesh with the gear, 28.

I have shown the various lengths of strip indicated by numerals on the face of 70 the cam, 23, adjacent to the respective notches, 24.

By the use of this invention, I avoid the necessity for changing the diameter of the drum for the marking of strips into sections 75 of different lengths.

What I claim as new and desire to secure by Letters Patent is—

1. In a strip-marker, and in combination, a rotatory drum; a frame movable toward and from the axis of the drum; a shaft rotatively mounted in said frame; a pair of gear-elements, one mounted upon said shaft, and the other mounted to rotate in unison with said drum, one of said elements comprising a gang of gears of different diameters adapted to be severally engaged by the other of said elements; means for simultaneously shifting one of said gear-elements to locate a selected gear of said gang opposite 90 the other gear-element, and for moving said frame to locate one gear-element in proper position with reference to the diameter of the selected gear of said gang; a marking-device co-operative with said drum and 95 means whereby it is adapted to be intermittently operated by rotation of said shaft.

2. In a strip-marker, and in combination, a rotatory drum; a frame movable toward and from the axis of the drum; a shaft rotatively mounted in said frame; a pair of gear-elements, one mounted upon said shaft, and the other mounted to rotate in unison with the drum, one of said elements comprising a gang of gears of different diameters 105 adapted to be severally engaged by the other gear-element; a marking-device co-operative with said drum; means whereby it is adapted to be intermittently operated by rotation of said shaft; another shaft rotatively mounted in said frame; a pinion and a notched spiral cam on said other shaft; a gear-rack slidably mounted on said frame in engagement with said pinion; a connection between said gear-rack and one of said gear-elements for shifting the latter to locate a selected gear of said gang opposite the other gear-element; and a stationary support for said cam adapted to engage the several notches therein.

3. In a strip-marker, and in combination, a rotatory drum; a frame movable toward and from the axis of the drum; a shaft rotatively mounted in said frame; a pair of gear-elements, one mounted upon said shaft, 125 and the other mounted to rotate in unison with the drum, one of said elements comprising a gang of gears of different diameters adapted to be severally engaged by the other gear-element; a marking-device co- 130

operative with said drum; means whereby it is adapted to be intermittently operated by rotation of said shaft; another shaft rotatively mounted in said frame; a pinion and 5 a spiral cam on said last-mentioned shaft; and a stationary support for said cam, said cam being provided with peripheral notches severally engageable with said support, spaced apart and numbered in accordance 10 with different lengths of strip-sections to be marked.

4. In a strip-marker, and in combination, a rotatory drum; a frame movable toward and from the axis of the drum; a shaft rotatively 15 mounted in said frame; a gear-wheel fixed on said shaft; a gang of gears of different diameters mounted to rotate in unison with the drum and capable of sliding movement longitudinally of the axis of the drum, the

gears of said gang being adapted to be severally engaged by said gear-wheel; a marking-device coöperative with the drum; means whereby it is adapted to be intermittently operated by rotation of said shaft; another shaft mounted in said frame; a 25 pinion and a spiral cam on said last-mentioned shaft; a pinion-engaging gear-rack slidably mounted upon said frame parallel with the axis of the drum; a member projecting from said gear-rack for slidably 30 shifting said gang of gears; and a stationary support for said cam.

In testimony whereof I have hereunto set my hand this 8th day of May, 1914.

OLIVER W. CURTIS.
